UNITED STATES PATENT OFFICE.

JOHN STUTIKA, OF WEST PULLMAN, ILLINOIS.

AUTOMOBILE ATTACHMENT.

1,405,352.

Specification of Letters Patent. Patented Jan. 31, 1922.

Application filed June 21, 1920. Serial No. 390,576.

To all whom it may concern:

Be it known that I, JOHN STUTIKA, a citizen of the United States, residing at West Pullman, Illinois, have invented certain new 5 and useful Improvements in Automobile Attachments, of which the following is a specification.

This invention relates to attachments for motor vehicles, and it comprises an overflow 10 pipe arranged in the cap of a radiator slightly above the usual overflow pipe, a three-way valve arranged therein, connections whereby steam may be delivered to the intake manifold, or condensed and delivered 15 to the cylinder for removing the carbon, the second connection being connected to a petcock which permits the delivery of water to the cylinder, but prevents the outflow of air or gases, thereby maintaining the compression 20 within the cylinder, said petcock having a second valved opening whereby air upon pressure may be discharged therefrom for cleaning spark plugs and the like.

In the present invention, I have provided 25 an attachment for motor vehicles whereby steam from the radiator is collected and may be delivered to the intake manifold to enrich the mixture. The delivery pipe is provided with a branch leading to a petcock or valve 30 in the head of the engine cylinder, whereby the steam may be first collected in the delivery pipe and then condensed and delivered to the cylinder while the engine is running, for the purpose of removing carbon from the 35 walls of the cylinder. The inlet is provided with check valves in the form of small balls which are adapted to prevent exhaust of gases from the cylinder through the inlet.

The valve or petcock in the head of the 40 engine cylinder is further provided with means for exhausting air or other gas under pressure from the engine cylinder when the engine is running, for the purpose of producing a blast for cleaning spark plugs and other purposes, and this outlet is provided 45 with an automatic check valve to prevent entrance of air through the nozzle on the inward stroke of the piston in the engine cylinder.

50 In the accompanying drawings, I have shown one embodiment of the invention. In this showing,

Figure 1 is a side elevation of a conventional type of engine showing the invention 55 applied.

Figure 2 is a vertical sectional view of the

top of the radiator showing the overflow pipe.

Figure 3 is a sectional view of the main valve at right angles to Figure 2. 60

Figure 4 is a detail perspective view of the valve plug.

Figure 5 is a vertical sectional view of one of the petcocks on the engine cylinders.

Figure 6 is a similar view at right angles 65 thereto.

Figure 7 is a horizontal sectional view on the line 7-7 of Figure 5, and

Figure 8 is a similar view on the line 8-8 70 of Figure 5.

Referring to the drawings, the reference numeral 1 generally designates an engine of the usual type provided with an intake manifold 2, exhaust pipe 3, and a water cooling radiator 4. These parts are of the usual construction and form no part of the present invention except in the combination claimed. 75

Referring in detail to Figure 2 of the drawings, the usual overflow pipe 5 is provided wherein steam produced by vaporization of the water in the radiator is exhausted from the cooling system. A second overflow pipe 6 is arranged in the head 7 of the radiator below the cap 8. As shown, the second overflow pipe is arranged with its upper 80 end slightly above the usual overflow pipe to prevent passage of any water in liquid form into the pipe. The space between the upper end of the pipe and the radiator cap 7 is sufficient to insure delivery of steam 85 thereto, when steam is formed in the radiator and prevent clogging in the end of the pipe. This pipe is curved as shown and is provided with a threaded end 9 adapted to be received in a coupling member 10 arranged 90 in the wall of the radiator. One end of the coupling member is provided with a flange 11 and a packing nut 12 is positioned on the opposite side of the radiator, suitable packing 13 being arranged between the flange 100 and the radiator wall and the nut and the radiator wall to prevent leakage. The end of the coupling is screw threaded and is adapted to be received within the main valve casing 14. As shown, this valve is provided 105 with a plug 15 having a pair of openings 16 and 17 arranged at approximately 90° from each other. The valve is also provided with a central bore 18 communicating with the interior of the coupling 10. The plug 110 is provided with a handle 19 on its outer end to permit manipulation of the valve. The

valve casing is provided with diametrically opposed outlets 20 and 21 connecting to branch conduits 22 and 23. The first mentioned conduit is a steam conduit and the 5 second mentioned one is the water conduit. As shown in Figure 1 of the drawings, the steam conduit is coiled about the exhaust pipe as at 24 and the opposite end thereof is connected to the intake manifold.

10 The water conduit is provided with a plurality of branches 25 corresponding in number to the number of cylinders, and these branch conduits communicate with valves or petcocks 26 arranged in the head of the engine cylinders.

15 The detail construction of the valve 26 is shown in Figures 5 to 8 of the drawings. As shown, the valve comprises a lower section having external screw threads 27 adapted 20 to be received in the screw thread opening in the head of the cylinder. The valve body is provided with a central bore or conduit 28. The upper portion of the valve casing 29 is provided with a reduced end 30 25 having screw threaded engagement with the member 26. This member is provided with a central bore 31 communicating with the bore 28. A member 32 is arranged on the member 26 and is adapted to be held in place 30 by the upper portion of the valve casing when it is placed in position. This member is provided with a central opening through which the lower reduced end 30 passes. As shown, the member is provided with radial 35 offset 33 having external screw threads adapted to engage internal screw threads in the end of the branch conduit 25. A central opening 34 is arranged in this member. The opening through which the reduced end of 40 the upper portion of the valve casing extends, is slightly enlarged, as at 35, to permit passage of water therethrough. The passage 35 communicates with openings 36 formed in the upper portion of the valve casing and 45 connected to an enlarged central opening 37 arranged therein. A plurality of small balls 38 are arranged over the openings 36. The enlarged opening 37 communicates with the central bore 31 by means of radial openings 39. The upper end of the valve comprises 50 a member 40 having external screw threads adapted to be received in internal screw threads in the upper portion of the valve casing. As shown, this member 40 is provided with a central bore 41 communicating with the bores 26 and 31. The members 29 and 40 are provided with diametrically opposed radial openings adapted to receive a plug 42 having an operating handle 43. The 55 plug 42 is tapered and is provided with a washer or plate 44 on the small end, held in place by a pin 45. A coil spring 46 is arranged between the valve casing and the plate 44 adapted to maintain the valve in 60 proper position. The plug is provided with 65

radial opening 47 whereby the central bore of the valve may be placed in communication with the atmosphere when the valve is in a position shown in Figure 6. The end of the bore is provided with a recess 48 70 adapted to receive a ball valve 49 to prevent passage of fluid inwardly. A perforated plate 50 is arranged in the bore 41 slightly spaced from the ball valve to maintain it in proper position. The upper end of the 75 member 40 is provided with an internally threaded recess 51 adapted to receive a nozzle 52 having external threads 53 engaging the threads in the recess.

The operation of this device is as follows: 80

Through the medium of the main valve 14, either of the conduits 22 and 23 may be placed in communication with the overflow pipe 6, or both of them may be closed. As shown, the opening 16 whereby steam is delivered to the outlet pipe 22, is larger than the opening 17 which is adapted to communicate with the water pipe 23. By proper operation of the valve plug 15 through the medium of handle 19, the overflow pipe 6 90 may communicate with the steam pipe 22 through the central bore 18 of the valve and opening 16. Steam is then delivered to the steam pipe 22, heated by the exhaust gases 95 in the coil 24 and delivered to the intake manifold to enrich the mixture.

When the driver of the machine desires to pass water therethrough to remove carbon from the walls of the entrance cylinder, the plug 15 of the valve is first moved to 100 closed position whereby communication with the two outlet pipes is interrupted. The valve is then moved to the position to bring the opening 17 in communication with the outlet 21 to deliver water to the pipe 23. This water passes into the valve 26 through the opening 34 in the radial projection 33, thence to the enlarged passage 35, to opening 36 to the passage 37, thence through passage 39 to the central bore of the valve and 110 is delivered to the cylinder. The balls 38 permit passage of fluid inwardly from the pipes 25 to the cylinder, but are seated by outward pressure to prevent overflow of gases outwardly from the cylinder. This prevents the loss or disturbance of the compression in the engine cylinder. In actual 115 operation, the valve 14 is maintained in closed position until the engine has been in operation for a short length of time before either steam or water is delivered to the engine cylinder. The valve is then forced 120 open to deliver water to prevent the possibility of obtaining any condensed steam in the fluid that is delivered to the intake manifold. When the valve has been in this position long enough to insure the removal of all water from the overflow pipe 6, it is moved to the proper position to feed steam to the steam pipe 22. In normal operation, 130

the plug 42 is maintained in the position shown in Figure 5 of the drawings to prevent exhaust of fluid under pressure by the nozzle 52. When the operator of the machine desires to obtain a blast of air or other gases for the purpose of cleaning spark plugs or for any other purpose, the plug is moved to the position shown in Figure 6 of the drawings, the opening 47 therein then being in alinement with the bore 41 permits passage of fluids compressed in the engine cylinder and a blast is obtained from the nozzle outlet which is very effectual for the purpose of cleaning spark plugs. The ball valve 49 is arranged in the bore 41 above the plug, for the purpose of preventing inflow of air through the nozzle 52 on the return stroke of the engine cylinder, the plate 50 being provided for the purpose of maintaining this ball valve in proper position.

It is to be understood that, while I have described the preferred embodiment of my invention, various changes in the shape, size, and arrangement of parts may be resorted to without departing from the spirit of the invention or the scope of the subjoined claims.

Having thus described my invention, I claim:

1. An attachment for internal combustion engines comprising a valve body secured at its lower end in the head of the engine cylinder, said valve body being provided with a bore extending throughout its length, a manually controlled valve mounted in

said valve body intermediate the ends thereof, means mounted in said valve body to prevent inflow through said manually controlled valve when the latter is in open position, and a check valve mounted in said valve body below said manually controlled valve to permit inflow into the bore of said valve body independently of said manually controlled valve. 40

2. An attachment for internal combustion engines comprising a valve body secured at its lower end in the head of the engine cylinder, said valve body being provided with a bore extending throughout its length, a manually controlled valve mounted in said valve body intermediate the ends thereof, said valve being provided with an opening, a check valve mounted in said valve body and adapted to seat in the upper end of the opening in the manually controlled valve when the latter is in the open position, an annular passage way formed in said valve body below said manually controlled valve and communicating with the bore in said valve body, said valve body being provided with openings communicating with said annular passage way, and ball check valves mounted in said last named openings to permit inflow into the bore of said valve body. 45 50

In testimony whereof I affix my signature in presence of two witnesses.

JOHN STUTIKA.
